UNITED STATES PATENT OFFICE

REMI J. GITS, OF CHICAGO, ILLINOIS

LUBRICATOR

Application filed December 6, 1930. Serial No. 500,523.

This invention relates to devices for supplying lubricating oil to the various bearings or journals of a machine.

- An object of the invention is to provide improved means for delivering lubricating oil at various rates to the different journals of a machine, and whereby the rate of delivery may be definitely predetermined to meet the exact requirements for each bearing. 5
10 A further object of the invention is to provide an improved device of this character wherein lubricating oil may be supplied from a central single container either by gravity feed or pressure feed, at different rates to a 15 plurality of conduits, each leading to a separate bearing.

The objects of the invention are accomplished by a construction as shown in the drawings, wherein:

Figure 1 is a front view of the lubricator, with the conduits leading therefrom to various bearings being shown broken away.

Fig. 2 is a transverse sectional view of the lubricator taken on the line 2-2 of Fig. 1.

Fig. 3 is a fragmentary perspective view showing a reciprocating cross head and oil carriers operated thereby, and the receiving conduits upon which these carriers are reciprocated.

Fig. 4 is a longitudinal sectional view of the lubricator.

Fig. 5 is a fragmentary sectional view similar to Fig. 4, but showing the oil carriers in their upper or delivery position.

Fig. 6 is an enlarged fragmentary sectional view taken on the line 6-6 of Fig. 4.

Fig. 7 is an enlarged fragmentary sectional detail showing the device equipped with a force feed attachment.

Fig. 8 is a sectional view similar to that shown in Fig. 7, but with the feeding plunger in its lower position.

The principal features of the construction by which this invention is carried into effect, 15 include an oil supply container having therein a plurality of conduits with inlet openings at one end above the normal oil level and the opposite ends connected to conduits leading to the various bearings of the machine to be lubricated. A cross head is ar-

ranged to reciprocate up and down in the oil container at regular intervals and carries means for lifting different quantities of oil to the open inlet ends of the oil receiving conduits. This cross head may be carried by 55 a pneumatically operated plunger or other means for imparting the desired reciprocating motion thereto. The cross head may also carry plungers arranged for forcing oil delivery to any of the conduits at the required 60 pressure for delivery in cases where gravity feed is not suitable.

Referring to the drawings, an oil supply container 1 is shown provided with a filling means 2, having an oil level indicator 3. The container 1 has a series of apertured bosses 4 on the bottom wall thereof, into which are tightly fitted tubes or oil conduits 5 having open upper ends 6, and their open lower ends 7 extending into the fittings 8 which provide 70 communication between the conduits 6 and conduits 9, leading to the various journals to be lubricated. The rate of feed of the lubricant through the fittings 8 may be seen through the glass covered sight openings 10 75 therein.

Mounted on the cover plate 11 of the container 1 is a cylinder 12 to which air under pressure may be delivered at required intervals through the inlet port 13. A piston 14 reciprocates within the cylinder 12 under the action of the air as it is admitted and released from the cylinder. A rod 15 extending downwardly from the piston 14 carries a cross head 16 which supports a plurality of 80 oil carriers 17, slidably mounted upon the conduits 5. The oil carriers are in the form of sleeves substantially fitting the conduits 5, except at the upper ends thereof, where they have enlarged bores 18, providing 85 pockets for carrying oil upwardly along the outer surfaces of conduits 5 and permitting such separated quantities of oil to flow into the open ends 6 of the conduits when the cross head is at the upper end of its stroke. The 90 pockets 18 vary in size and therefore, different quantities of oil will be delivered to the different conduits 5 upon each stroke of the cross head. The oil measuring sleeves are assembled in the cross head 16 by passing 95 100

them between the two bars 19 of the cross head at the cut-away parts 20 of these bars and sliding them along the bars. The bars 19 of the cross head fit within the annular grooves 21 cut on the outer surfaces of the sleeves 17.

With the arrangement above described upon each upward stroke of cross head 16, the pockets 18 of the sleeves or oil measuring devices 17 lift different definite quantities of oil to the inlets of the different conduits 5 according to the oil carrying capacity of the pockets 18. The delivered oil may then flow by gravity through the conduits 5 and conduit connections 9 therewith to the different parts of the machine which is to be lubricated.

In case gravity feed cannot be relied upon, the cross head 16, as shown in Figs. 7 and 8, carries posts 22 supporting a bar 23 from which depend plungers 24 which fit and enter the tubes 5 on the down stroke of the plunger, and force the oil in the conduits 5 past a check valve 25 shown in the lower end thereof.

In order to modify the delivery of oil of all the carriers, an adjusting means 26 is provided for regulating the upward stroke of piston 14. This means is shown as a thumb screw threaded into the cap of cylinder 12 and affords a fine adjustment so that the limit of upward movement of the oil carriers 17 may be exactly regulated as desired.

In the operation of this lubricator, the oil level in the container 1 is maintained by any desired means such as automatic float controlled feed thereto. The manner of reciprocating the cross head 16 is also not essential to this invention, as various appliances are suitable for such purpose.

It is intended that it be reciprocated either at such intervals or regular rate as to insure the delivery of only the required amount of oil to each of the conduits leading to the bearings of the machine which is to be lubricated.

The measuring devices 17 having different oil carrying capacities will, upon each reciprocation, deliver different quantities of lubricant to the conduits 5. When at the upper ends of their stroke, the oil drains from these carriers into the open ends of conduits 5 and flows by gravity from these conduits into the conduits 9 and into the machine bearings. In cases where gravity feed is not convenient for any particular bearing, the delivery of the oil is insured by means of the plungers 24 which serve to force it through the conduits.

Although but one specific embodiment of this invention has been herein shown and described, it will be understood that certain details of the construction shown may be altered or omitted without departing from the spirit of this invention as defined by the following claims:

I claim:

1. A lubricator comprising an oil supply container, said container being provided with an oil conduit extending upwardly therein, and having an inlet for oil above the normal oil level, an oil carrier slidable along said conduit for carrying oil upwardly to the conduit inlet, means for reciprocating said oil carrier, and a plunger movable with said oil carrier and fitting within said conduit for forcing the delivered oil through the conduit. 70

2. A lubricator comprising an oil supply container, said container being provided with an oil conduit extending upwardly therein, and having an inlet for oil above the normal oil level, an oil carrier slidable along said conduit for carrying oil upwardly to the conduit inlet, means for reciprocating said oil carrier, a plunger movable with said oil carrier and fitting within said conduit for forcing the delivered oil through the conduit, and means for preventing backward flow of oil through said conduit. 80

3. A lubricator comprising a supply container, a plurality of tubes mounted within said container and extending vertically therein so that their upper ends extend above the oil in said container, inlet openings at the upper ends of said tubes, oil carrying tubes communicating with the lower ends of said tubes, sleeves slidably mounted upon said tubes, said sleeves being provided with oil carrying pockets, means for reciprocating said sleeves along said tubes whereby oil in the pockets of said sleeves will be delivered to the inlet openings at the upper ends of said tubes, said means comprising a carrying member for said sleeves, and means attached to said carrying member for lifting and lowering it at regular intervals. 90

Signed at Chicago this 2nd day of Dec., 1930.
